Patented June 13, 1922.

INVENTOR,
H. Lund Smith
John Edward.
ATTORNEY.

UNITED STATES PATENT OFFICE.

HENRY LUND SMITH, OF PATERSON, NEW JERSEY.

VISION SHIELD.

1,419,321.

Specification of Letters Patent. Patented June 13, 1922.

Application filed September 21, 1920. Serial No. 411,724.

To all whom it may concern:

Be it known that I, HENRY LUND SMITH, a citizen of the United States, residing at Paterson, in the county of Passaic and State 5 of New Jersey, have invented certain new and useful Improvements in Vision Shields, of which the following is a specification.

The object of this invention is to destroy the glare of the light of an approaching vehicle in riding at night while preserving the visibility, it being within the object of the invention also that the driver be not required to change his point of view. This object I accomplish by providing a shield 10 composed of a series of translucent areas and a series of clear-vision areas arranged in alternation with the translucent areas and respectively immediately adjoining and being also appreciably narrower than the 15 translucent areas as viewed by the user when said series intervenes between him and the objective and stands substantially perpendicular to his line of vision. By this form of shield the two kinds of areas have a distinct 20 cooperation with each other, that is, their effect on the driver's eyes is more or less a blended one, to the end that whereas the visibility is retained the glare is destroyed, and this without the driver shifting 25 his point of vision. In the preferred form each translucent area consists of a translucent body, as a vane, having surfaces inclined forward and downward from the observer's side of the shield so that he will 30 have the required better view of the road forward of and more or less nearer his own vehicle than where the approaching light is. By the use of my invention the element of 35 safety on roads at night is greatly increased, principally because the lights on vehicles do not have to be dimmed, according to the present custom, but can be used at full illuminating power and unobscured. A further object is to provide such a construction 40 and arrangement of essential parts as to produce an article of manufacture of substantially the nature of that specified above which may be readily attached and adjusted to suit the requirements of the driver or 45 user and which shall be inexpensive to manufacture and strong and durable.

In the accompanying drawing,

Figure 1 is a rear view of the shield shown mounted on the wind-shield of an automobile; and

Figure 2 is a vertical sectional view of what is shown in Figure 1, being taken on line 2—2 in that figure.

a designates the aforesaid series of spaced plates, sheets or vanes arranged in approximately parallel planes each oblique to the series and each vane being translucent, that is, capable of transmitting light rays without permitting objects to be distinctly seen therethrough. The material of the vanes 65 may be ground or frosted, or suitably colored (as green), glass or, preferably, celluloid or equivalent infrangible substance.

For the support of these vanes I preferably provide the following structure:

There is a rib *b*, which in cross-section is T-shaped to give it strength with lightness and which extends longitudinally of the series, or transversely of its component vanes, and is preferably arranged about midway 75 between the ends of the vanes, which are all of the same length, and back of them, the rear of the device being to the right as it is seen in Figure 2. This rib is formed with a recess *c* at the front thereof (that is, in 80 the vertical web of the T) which receives the series of vanes. At the top it has an extension or head *d*, preferably formed flat, and near the bottom and on the back it has a knob *e*.

Two U-shaped members *f*, preferably formed of sheet metal and secured at their bent-off ends *g* to the opposite sides of the rib *b* at points above and below the recess *c*, are provided, they being reverse counterparts of each other and serving as a marginal frame for the vanes. At suitably spaced and oblique points these members have in their upright portions *f* rebends *h* which form at the inside grooves in which the ends 95 of the vanes are received and suitably secured.

The wind-shield of an automobile is indicated at *i*, and this may serve as a suitable means to which to attach my device. Thus 100 I provide a clamp *j* having a suitable clamping device (such as a set-screw *k*) which has

a fork-shaped head *l* receiving the head *d* of rib *b*, the two heads being penetrated by a screw-bolt *m* so that a pivotally adjustable connection is formed. The device is shown 5 secured by the clamp to the top of the windshield.

In the operative position of my vision shield it is adjusted to stand more or less in the position shown by full lines in the drawing. In this position, since the vanes *a* are translucent and have some transparency the driver is not blinded by the light of a vehicle ahead of him and yet he has a fair vision ahead, but more or less near and ahead of 10 the vehicle he has a perfectly unobstructed vision (downwardly between the vanes) so that he can see and thus avoid irregularities in the road and other objects which he is only expected to see at short range. Even 15 if the shield were swung forward on its pivot from the position shown in Figure 2, so that there would be clear visibility between the vanes in the direction of an approaching light, I find in practice, since in 20 the example illustrated the vanes and spaces are all horizontal, that the vision is not embarrassed by the glare of the approaching light, especially as the up and down motion of the vehicle incident to its travel over the 25 road produces a shifting of the shield and the driver's eyes relatively to each other so that the glare is constantly interrupted by the translucent vanes. In short, the rays of light passing through the translucent area 30 and clear vision area are in effect blended, so that the visibility is retained but the glare is destroyed, and this, moreover, without the driver changing his point of view.

In the daytime, or otherwise when the 35 device is not in use, it may be swung up to the position shown by dotted lines in Figure 2.

Having thus fully described my invention,

what I claim and desire to secure by Letters Patent is:

1. A vision shield composed of a series of translucent areas and a series of clear-vision areas arranged in alternation with the translucent areas and respectively immediately adjoining and appreciably narrower than the translucent areas as viewed by the user when said series intervenes between him and the objective and stands substantially perpendicular to his line of vision. 45

2. A vision shield composed of a series of translucent areas and a series of clear-vision areas arranged in alternation with the translucent areas and respectively immediately adjoining and appreciably narrower than the translucent areas as viewed by the user 50 when said series intervenes between him and the objective and stands substantially perpendicular to his line of vision, the translucent areas consisting of translucent bodies having surfaces inclined forward and downward from the observer's side of the shield. 55

3. The combination of a series of vanes arranged in approximately parallel planes, and a frame for said series including sheet metal side members rigidly connected to 60 each other and having rebends forming recesses at the inside receiving and holding the ends of the vanes. 65

4. In a light obstructing device, the combination of a series of vanes arranged in approximately parallel planes, and a frame for said series including a rib member extending longitudinally of said series in a plane cutting each vane between its ends, and reverse U-shaped marginal supporting 70 members attached to said rib member and receiving and holding the respective ends of the vanes. 75

In testimony whereof I affix my signature.

HENRY LUND SMITH.
